(57) **CLAIM**

The ornamental design for a cylindrical sign display, as shown and described.

DESCRIPTION

FIG. 1 is a front perspective view of a cylindrical sign display, showing my design;

FIG. 2 is a front elevational view thereof;

FIG. 3 is a rear elevational view thereof;

FIG. 4 is a right side elevational view thereof; and,

FIG. 5 is a left side elevational view thereof.

The varying stippled shading represents contrasting appearance. The broken line showing in the Figures illustrates environment and forms no part of the claimed design.
